UNITED STATES PATENT OFFICE

2,584,457

LAP PIN AND CALENDER RACK

Fred Hunter, Lancaster, S. C., assignor to Precision Gear & Machine Company, Charlotte, N. C., a corporation of North Carolina

Application November 9, 1946, Serial No. 709,038

3 Claims. (Cl. 19—162)

1

This invention relates to an improved lap pin having anti-friction properties and calender racks associated therewith to prevent the ends of the lap pin from rotating in the calender racks. Heretofore, a lap pin has usually been composed of a straight rod, onto which the lap of fibers is wound in a picker, and the like, and the ends of this lap pin have been pressed downwardly by means of calender racks, sometimes referred to in the trade as loggerheads. The conventional calender racks have rollers therein and the ends of the lap pin rotated in the hooked portions of the calender racks. This has resulted in wearing of the ends of the lap pin and producing defective lap rolls.

It is an object of this invention to provide a lap pin onto which a lap of fibers is wound with the lap pin comprising an elongated sleeve onto which the lap of fibers is wound and said sleeve being penetrated by a rod whose ends project substantially beyond the ends of the sleeve, with ball bearings disposed between the sleeve and the rod, whereby the rod will remain stationary and the sleeve will rotate along with the lap roll. This will result in the ends of the rod not rotating, but being held stationary and in order to insure that the rod will not rotate, the calender racks, instead of having roller bearings therein for engaging the lap pin, have friction surfaces, such as a pad of leather, fabric and the like, to frictionally engage the ends of the rod to retard rotative movement thereof so that the sleeve will do the rotating and the rod will remain stationary.

Some of the objects of the invention having been stated, other objects will appear as the description proceeds, when taken in connection with the accompanying drawings, in which

Figure 1 is an elevation of my improved lap pin;

Figure 2 is a longitudinal sectional view taken substantially along the line 2—2 in Figure 1;

Figure 3 is a sectional view taken along the line 3—3 in Figure 1;

Figure 4 is a transverse sectional view taken along the line 4—4 in Figure 2;

Figure 5 is an end elevation of a portion of a picker and the like showing the lap roll held by a pair of calender racks;

Figure 6 is an end view looking at the right-hand end of Figure 5;

Figure 7 is a vertical sectional view taken along the line 7—7 in Figure 5.

Referring more specifically to the drawings, the numeral 10 indicates a sleeve. Penetrating

2

the sleeve, and projecting from both ends thereof, is a shaft 11 which has a bore 12 extending from one end thereof to near the handle end 13, said bore 12 stopping at the point 14. 5 Mounted on the rod 11 are raceways 16 and 17 and mounted in the inside and at the end portions of the sleeve 10 are raceways 18 and 19, and between these raceways are disposed balls 20, and which balls 20 are sealed by annular flat 10 rings 21, whereby the sleeve 10 will rotate by means of the ball bearing relative to the rod 11 since the sleeve has an inside diameter substantially greater than the rod 11. The bore 12 in the rod 11 is conventional in the old-style 15 of lap pin and is for the purpose of inserting a smaller pin in the bore 12 before the roll of fibers is doffed from the lap pin so that the roll of fibers will be doffed onto the smaller pin which will be used for handling purposes, while the 20 lap pin proper will be reinserted in the picker for the formation of a new lap roll.

In Figures 5, 6 and 7 portions of a picker are shown, in which the frame members 25 and 26 have mounted therein suitable calender rolls 25 27 and 28 on which the lap roll 29 is adapted to be formed. In a picker of this type there are calender racks 30 and 31 whose lower ends have a rack thereon, each of which is engaged by a pinion, not shown, which are controlled by the 30 picker for moving the calender racks upwardly in proportion to the diameter of the roll as it is being formed. These old-style calender racks had a hooked portion 33 at the top thereof in which rollers were mounted for contacting the 35 ends of the lap pin and the lap pin rotated in the calender racks.

In the present form of the invention there is secured in the hooked portion of each of these calender racks a flat piece of friction material 40 35, such as leather, which contacts the end of the shaft 11, and this tends to prevent rotation of the shaft 11 to thus permit the sleeve 10 to rotate relative to the shaft 11 while the shaft 11 remains stationary.

45 It is thus seen that I have provided an improved lap pin in which the lap receiving portion rotates but which portion is rotatably mounted on a shaft which is engaged by friction material disposed in the calender racks to prevent rotation of the shaft but permitting rotation of the sleeve mounted on the shaft and said sleeve having sealed ball bearings so as to provide for easy running and long life.

50 In the drawings and specification there has been set forth a preferred embodiment of the

invention, and although specific terms are employed, they are used in a generic and descriptive sense only, and not for purposes of limitation, the scope of the invention being defined in the claims.

I claim:

1. In a picker having calender rolls and a pair of calender racks for engagement with a lap pin onto which a lap of fiber is wound for pressing the lap of fibers against the calender rolls, said lap pin comprising a shaft having its ends extending beneath the calender racks, each of the calender racks having friction material therein for engaging the shaft and exerting downward pressure on the same, said shaft being surrounded by a sleeve member having a greater inside diameter than the outside diameter of the shaft, a ball bearing disposed between each end of the sleeve and the shaft whereby the sleeve member will rotate relative to the shaft and the friction material in the calender racks will prevent rotation of the shaft. 15

2. In a picker having a pair of calender racks provided with friction surfaces for engaging a lap pin, said lap pin comprising an elongated member whose ends are adapted to be engaged by the friction surfaces in the calender racks, a sleeve rotatably mounted on the elongated member and adapted to receive a lap roll of fibers, anti-friction bearings disposed between the 20 25 30

inner surface of the sleeve member and the exterior of the elongated member.

3. A lap pin for pickers comprising a shaft, a sleeve member surrounding an intermediate portion of the shaft and adapted to receive a lap of fibers, the inside diameter of the sleeve being substantially greater than the outside diameter of the shaft, anti-friction bearings disposed between the shaft and the ends of the sleeve member, said shaft having a longitudinally extending bore extending from one end thereof for a distance greater than the length of the sleeve but stopping short of the other end of the shaft for reception of a smaller pin. 5

FRED HUNTER.
